SPRING STRUCTURE

Lawrence H. Hamilton, Niles, Mich., assignor to
National Standard Company, Niles, Mich., a
corporation of Michigan

Application November 9, 1936, Serial No. 109,841

4 Claims. (Cl. 5—267)

This invention relates to springs, and is illustrated as embodied in a novel bed spring or the like intended to support an "inner-spring" or other form of yielding mattress.

5 An object of the invention is to provide a spring support such as a bed spring having a large part of its upper surface arranged yieldingly to support loads, while at the same time the major part of the spring structure consists of individually-
10 yieldable vertically-arranged relatively strong coil springs arranged in the usual rows or other pattern.

To this end, between the rows of the vertical springs I arrange (substantially in the plane of the upper ends of the vertical springs) lengthwise-yieldable parallel wide bands or supports, arranged in one direction of the structure, while in the other direction (i. e. at right angles to the yieldable supports) I arrange tensioned horizontal coil springs which engage and support the wide parallel bands between the rows of vertical springs. Preferably these horizontal springs encircle and attach together the top coils of adjacent ones of the vertical springs.

25 I prefer to use, for the parallel wide supports, braids of spring steel wire constructed as described below to form in effect a great number of small flat springs yieldable in the plane of the supports. I also consider it desirable at least partially to close the spaces within the upper coils 30 of the vertical springs by continuing those coils in a flat or plane spiral toward the axes of their respective springs.

The above and other objects and features of the 35 invention will be apparent from the following description of the illustrative embodiment shown in the accompanying drawing, in which:

Figure 1 is a top plan view of one corner of a 40 bed spring embodying the invention;

Figure 2 is a partial vertical section therethrough;

Figure 3 is a bottom plan view, on an enlarged scale, of one end of one of the flat supports, with a slightly different means for attaching it to the 45 frame than is shown in Figure 1;

Figure 4 is a section through the support on the line 4—4 of Figure 3;

Figure 5 is a side elevation of part of the attaching clip of Figure 3; and

50 Figure 6 is a plan view of the blank from which the attaching clip is formed.

The novel bed spring shown in Figures 1 and 2 includes the usual series of vertically-arranged coil springs 10, arranged in rows with each row 55 supported by a suitable transverse stamping or

other support 12 carried by the lower frame of the spring which, in Figure 1, is directly below an upper frame 14 (which may be made of steel stampings riveted together), and which upper frame surrounds the vertical springs 10 substantially in the plane of their upper ends.

As appears in Figure 1, I prefer to close (at least partially) the space within the upper coil of each of the vertical springs 10 by continuing the upper coil toward the axis of the spring as a 10 flat spiral in the plane of the top coil.

The space between the rows of vertical springs 10, at their upper ends, is occupied by spring wire bands or parallel flat wide supports 16 tensioned between the opposite ends of the upper frame 14, 15 substantially in the plane of the upper coils of the vertical springs 10. These spring bands are preferably somewhat more yielding than the vertical springs 10.

I prefer to use for these parallel supports wide 20 flat spring steel tapes consisting of braids of steel wire, expanded widthwise to spread the wires apart to give a relatively open mesh and give the support a very considerable width. The ends are provided with clips 18 having portions hooking 25 into slots in the frame 14 and other portions embracing and gripping the ends of the braids.

The clips 18 in Figure 1 compact and bind together the wires at the ends of the braids, so that 30 they are not as wide as the body of the braid. However, I may alternatively use clips 118 of the form shown in Figures 3, 4, and 5, bent up from the blank 120 shown in Figure 6, and which are substantially the same as the clips 18 except that 35 they grip the entire width of the expanded braid 16.

Each of the braids 16 preferably consists of a series of spring steel wires, each extending for the full length of the braid, and each of which extends alternately over and under the other wires 40 diagonally across the braid. The braid, formed with an open mesh or expanded widthwise to form such a mesh, is heavily compressed so that the return bends of the wires along the opposite 45 edges of the braid are compressed beyond the elastic limit of the steel, to "set" the wire in a series of interbraided flat spring loops each of which yields in the plane of the braid, so that the braid is elastic lengthwise like a rubber band. 50

Elongation of the braid under load of course temporarily contracts the braid widthwise, but not sufficiently to interfere with its cooperative load-supporting function.

Alternatively the expanded or open-mesh braid 55

may be made of high-carbon wire drawn while soft, and tempered after the braid is formed.

At right angles to the supports 16 I arrange horizontal coil springs 34, each preferably threaded onto the upper coils of adjacent pairs of vertical springs 10 to encircle them and tie them together, as shown in Figure 2. While these horizontal springs 34 may if desired actually be attached to the supports 16, I prefer that they should merely underlie them between the rows of vertical springs 10, to engage and support them yieldingly under load, and to transmit part of the load from the supports 16 to the vertical springs 10.

While one illustrative embodiment has been described in detail, it is not my intention to limit the scope of the invention to that particular embodiment, or otherwise than by the terms of the appended claims. The present application is a continuation in part of my application No. 67,833, filed March 9, 1936.

I claim:

1. A spring structure comprising a plurality of rows of vertically-arranged coil springs and upper and lower frames surrounding said springs and the lower of which is provided with means supporting the lower ends of said springs, lengthwise-yieldable parallel wide supports each connected at its ends to the upper frame and arranged between each two rows of springs in one direction of said structure substantially in the plane of the upper ends of said springs, and each of which comprises a flat braid made up of spring steel wires each extending the full length of the braid and which wires are carried alternately over and under each other diagonally of the braid and which are spread apart to form a relatively wide mesh and which bend back across the braid at the edges thereof and are permanently set beyond the elastic limit of the steel at said edges to form in effect a large number of small springs yieldable in the plane of the braid, and horizontally-arranged tensioned coil springs arranged at right angles to said supports between said vertically-arranged springs and which encircle and secure together the top coils of adjacent pairs of vertically-arranged springs and which engage and support said parallel wide supports between said rows of vertically-arranged springs.

2. A spring structure comprising a plurality of rows of vertically-arranged coil springs and upper and lower frames surrounding said springs and the lower of which is provided with means supporting the lower ends of said springs, length-

wise-yieldable parallel wide supports each connected at its ends to the upper frame and arranged between each two rows of springs in one direction of said structure substantially in the plane of the upper ends of said springs, and horizontally-arranged tensioned coil springs arranged at right angles to said supports between said vertically-arranged springs and which encircle and secure together the top coils of adjacent pairs of vertically-arranged springs and which engage and support said parallel wide supports between said rows of vertically-arranged springs.

3. A spring structure comprising a plurality of rows of vertically-arranged coil springs and upper and lower frames surrounding said springs and the lower of which is provided with means supporting the lower ends of said springs, lengthwise-yieldable parallel wide supports each connected at its ends to the upper frame and arranged between each two rows of springs in one direction of said structure substantially in the plane of the upper ends of said springs, and each of which comprises a flat braid made up of spring steel wires each extending the full length of the braid and which wires are carried alternately over and under each other diagonally of the braid and which are spread apart to form a relatively wide mesh and which bend back across the braid at the edges thereof and are permanently set beyond the elastic limit of the steel at said edges to form in effect a large number of small springs yieldable in the plane of the braid, and horizontally-arranged tensioned coil springs arranged at right angles to said supports between said vertically-arranged springs and which engage and support said parallel wide supports between said rows of vertically-arranged springs.

4. A spring structure comprising a plurality of rows of vertically-arranged coil springs and upper and lower frames surrounding said springs and the lower of which is provided with means supporting the lower ends of said springs, lengthwise-yieldable parallel wide supports each connected at its ends to the upper frame and arranged between each two rows of springs in one direction of said structure substantially in the plane of the upper ends of said springs, and horizontally-arranged tensioned coil springs arranged at right angles to said supports between said vertically-arranged springs and which engage and support said parallel wide supports between said rows of vertically-arranged springs.

LAWRENCE H. HAMILTON.
